UNITED STATES PATENT OFFICE.

HENRY HELLWEG, OF MILWAUKEE, WISCONSIN, ASSIGNOR OF ONE-HALF TO LOUIS SCHLESINGER, OF MILWAUKEE, WISCONSIN.

TRUNK-FASTENING.

1,313,687.

Specification of Letters Patent.

Patented Aug. 19, 1919.

Application filed October 31, 1917. Serial No. 199,415.

To all whom it may concern:

Be it known that I, HENRY HELLWEG, a citizen of the United States, residing at Milwaukee, in the county of Milwaukee and 5 State of Wisconsin, have invented certain new and useful Improvements in Trunk-Fastenings, of which the following is a specification, reference being had to the accompanying drawing, forming a part 10 thereof.

This invention relates to trunk fastenings for fastening trunks, tool boxes etc., to the running boards of automobiles or other supports and in this specification and the claim 15 15 appended hereto the word "trunk" is used in a generic sense to mean a trunk, a tool box or any similar or equivalent receptacle.

Referring to the drawings which accompany this specification and form a part 20 hereof, which drawings illustrate an embodiment of this invention, and on which drawings the same reference characters are used to designate the same parts wherever they may appear in each of the several 25 views, Figure 1 is a front elevation of a trunk secured to a support; Fig. 2 is a transverse section taken on the line 2—2 on Fig. 1, looking in the direction indicated by the arrows; Fig. 3 is a longitudinal section 30 taken on the line 3—3 on Fig. 2, looking in the direction indicated by the arrows; Fig. 4 is an end elevation of part of a trunk illustrating a modified form of construction, parts being broken away and the support 35 being shown in section; and Fig. 5 is a longitudinal section taken on the line 5—5 on Fig. 4, looking in the direction indicated by the arrows.

Referring to the drawings, the reference 40 numeral 1 designates a trunk, 2 a support such as the running board of an automobile, for example, and 3 a clamp. The clamp is illustrated by the drawings as provided with an arm 4 which has separated bearings 5 and 6 and a clamping member or screw 7 which is adapted to engage the opposite side of the support 2 at a point between the bearings 5 and 6. This construction gives a three-point contact and an exceedingly firm grip

for the clamp. A lock nut 8 on the screw 7 50 can be jammed against the clamp to prevent the screw turning in the screwthreaded bore in the clamp and slackening its grip due to jars or vibrations. The screw has a handle 9 provided with apertures 10 and 11 for a 55 padlock 12. A bail 13 is pivoted to the clamp 3 by a pivot 14 and can be turned to be engaged with or disengaged from the handle 9 to prevent the handle and screw from being turned. The padlock 12 pre- 60 vents the bail 13 from being disengaged from the handle 9 by an unauthorized person. The bail and the padlock provide the clamp with locking means.

Referring to Figs. 1, 2 and 3 of the drawings, the trunk 1 is provided with means to be gripped by the clamp in the following manner. Apertures 15 are made in the side of the trunk adjacent its bottom to receive the arms 4 of clamps. Tubes 16 are secured 70 on the interior of the trunk so that the apertures 15 are not in communication with the interior of the trunk whereby the contents of the trunk and its interior are protected from dirt and moisture. Slats 17 may be 75 provided directly under the tubes 16, when the arms 4 of the clamps bear directly against the bottom 18 of the trunk and when the bottom of the trunk is elevated by its fittings such as corner pieces 19, and 80 escutcheons 20 may be applied to the trunk over the apertures 15 both for the sake of appearance and as strengthening plates.

Referring to Figs. 4 and 5 of the drawings, instead of having the arms 4 of the 85 clamps extend into the trunk, one or more plates 21 may be secured to the outside, or ends, of the trunk to be gripped by the clamp. Preferably a plate 21 is hinged to the trunk so that it can be folded against the 90 trunk as shown in dotted lines on Fig. 5 of the drawings. A flange 22 prevents the clamp from being twisted to release the trunk and performs the same function in this respect as the construction illustrated 95 by Figs. 1, 2 and 3 of the drawings.

Means, such as the flat spring 23 which can bear against either of the flat faces 24

or 25, may be provided for locking the plate 21 either in its extended or in its folded positions.

What is claimed is:

- 5 The combination with a trunk provided with an aperture and a tube on the inside of the trunk in line with said aperture, the inner end of said tube being closed, of a clamp

provided with an arm adapted to extend through said aperture into the trunk and 10 also provided with a clamping member, and means for locking the clamp to prevent the unauthorized removal of the trunk.

In witness whereof I hereto affix my signature.

HENRY HELLWEG.
